UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

STOP MECHANISM.

Application filed May 23, 1919. Serial No. 299,115.

To all whom it may concern:

Be it known that I, ERASTUS E. WINKLEY, a citizen of the United States, residing at Lynn, in the county of Essex and State of Massachusetts, have invented certain new and useful Improvements in Stop Mechanisms; and I do hereby declare the following to be a full, clear, and exact description of the invention, such as will enable others skilled in the art to which it appertains to make and use the same.

This invention relates to stop mechanisms for automatically disconnecting a driven mechanism from a driving mechanism under predetermined conditions of load, and for insuring the reconnection of said driven mechanism thereto in stepped time relation to other driven mechanisms that are operated thereby.

Letters Patent No. 1,163,799 granted Dec. 14, 1915 to the present applicant, discloses and claims a mechanism of this general character in which the driven machine is connected to the driving shaft through a worm drive which is normally maintained in operative relation by means of a yielding coupling that is acted upon by a heavy power spring. Under predetermined load conditions, the working relation of the worm drive is interrupted by the yielding of the coupling, the compression of the spring, and the disconnection of the source of power. The energy thus stored in the spring is utilized to reestablish the working relation of the worm drive and to insure the proper time relation between the interrupted driven machine and the other machines operated by the driving shaft, when the obstruction or cause of the overload condition is removed and power is again supplied to the driving shaft.

Although this mechanism accomplishes the ends in view effectively and simply, there exists a possibility of injury both to the operator and to the relatively light and delicate parts of the machine, when the obstruction is removed by the operator and the machine is suddenly moved ahead into its previous time relation or step through the action of the heavily compressed spring.

One of the objects of the present invention is to provide improved means of this general class for completely disconnecting one of a plurality of driven mechanisms from a common driving member upon the

occurrence of a predetermined overload, and for safely and reliably reconnecting said mechanism therewith, in timed relation with the other driven mechanisms, when the obstruction causing the overload is removed, 60 without danger to the operator or injury to the apparatus.

To this end, one feature of the invention resides in the provision of mechanism for immediately and completely disconnecting 65 a machine from its driving shaft under said overload conditions through disconnecting a safety clutch, and for subsequently tripping out a main clutch to cut off the supply of power to the driving shaft and any other 70 machines operated thereby. The reconnection of the machine to the driving shaft through the safety clutch, after the cause of the overload is removed and the main clutch is thrown in to supply power thereto, is controlled by means of an automatic timing device comprising cooperating timing members and sets of differential gearing that are 75 respectively connected to the machine and the driving shaft and which are so constructed and arranged as to cause the safety clutch to become operative to drive the idle machine only when the initial time relation or step of the machines is restored. The 80 cooperating timing members normally operate in unison or in step in accordance with the timed operation of the machine and the driving shaft, but when the machine is disconnected from the shaft, the out-of-step relation is reproduced by the timing members 85 until such time as the shaft and other machines connected thereto are again brought into coincident step or time relation, at which instant the safety clutch is automatically thrown in to reconnect the 90 machine and resume the normal operation.

Another object of the invention contemplates the provision of an automatic safety or overload clutch which shall fully protect the machine with which it is employed during all portions of its cycle of 100 operation and irrespective of the variation and distribution of load throughout the cycle.

A feature of the invention by means of 105 which this result is attained, comprises a yielding safety clutch, the setting of which is automatically varied throughout different portions of the cycle of operation of the machine by means of cam operated mechanism 110

designed to progressively adjust the clutch spring in accordance with the ultimate permissible loads during the various portions of the cycle of operation.

5 The invention further consists in other novel features of construction, combination and arrangement of parts, hereinafter described and particularly pointed out in the claims, the advantages of which will be apparent to those skilled in the art.

10 The various features of the invention will be readily understood from an inspection of the accompanying drawings and a perusal of the following detailed description

15 of the mechanism shown therein.

In the drawings, Figure 1 is a view in elevation of two machines which are driven from a common driving shaft, illustrating the manner of applying the present invention to one of the machines; Fig. 2 is an enlarged detail view, partly in longitudinal section and partly in elevation, of the timing device; Fig. 3 is a sectional view on the line 3—3 of Fig. 1; Fig. 4 is a sectional view 25 on the line 4—4 of Fig. 1; Fig. 5 is a sectional view on the line 5—5 of Fig. 1; and Figs. 6 and 7 are fragmentary detail views showing different relative positions of certain of the parts illustrated in Fig. 1.

30 Referring to Fig. 1 of the drawings, the invention is illustrated as applied to a machine 10 which is to be operated in timed relation with one or more other machines 12. The two or more machines 10 and 12 are each driven from a main driving shaft 14 through suitable driving connections which are indicated generally at 16 and 18, respectively. The driving mechanism for actuating the main shaft 14 comprises a main clutch, one 35 member 20 of which is secured to the shaft and the other member 22 of which is secured to a driving pulley 23 that is loosely mounted on the shaft and is connected by a belt 24 with a suitable source of power. A 40 loose pulley 25 is mounted on the shaft 14, at the side of the driving pulley 23, onto which the belt 24 may be shifted when the machine is not in operation. The clutch member 22 is provided with two holes 26

45 that are adapted to be engaged by clutch pins 27 which extend through holes in the clutch member 20 and are secured in a disk 28 that is loosely mounted on the shaft. The disk 28 is forced in a direction to engage 50 the pins with the holes in the clutch member by a spring 29, and the disk is provided with wedge blocks 30 which are adapted to be engaged by an inclined cam face 31 on a clutch controlling lever 32. The rear 55 end of the clutch controlling lever 32 is connected to a rod 33 arranged to slide vertically through a bearing 34, and forced in a direction to carry the end of the lever into the path of the wedge blocks 30 by a spring 60 35. When the clutch controlling lever is

raised into the position indicated in Figs. 1 and 4, it is out of the path of the wedge blocks 30, and the clutch pins engage the holes in the clutch member 22 so that the shaft 14 is continuously driven. The 70 clutch controlling lever 32 is normally held in this position, against the tension of the spring 35 by a latch 36 (Fig. 1) arranged to engage a collar 37 on the rod 33. When the latch 36 is disengaged from the collar 75 37, the clutch controlling lever is moved into the path of the wedge blocks 30, so that the clutch pins are withdrawn to throw out the driving mechanism for the shaft 14. The latch may be thus disengaged from the collar 80 37 by a sleeve 38 mounted to slide on the rod 33, and connected by a link 39 with an arm 40 secured to a rock shaft 42.

In accordance with the present invention the driving connections 16, by means of which the machine 10 is driven, include an auxiliary safety clutch comprising two clutch members 44 and 46 which permit the machine to be immediately disconnected from the main driving shaft 14 under predetermined overload conditions. The clutch member 44 comprises a disk having a hub which is secured to the shaft 14 and a laterally projecting lug 48 that is formed with an inclined driving face 50. The clutch member 95 46 consists of a sleeve which is loosely mounted on the shaft 14, and is provided, at one end with a laterally projecting ear, carrying a roll 52, that is normally engaged by the face 50 of the lug 48, so that the clutch member 46 is driven thereby. The clutch member 46 is provided with gear teeth 54, near the end of the member which carries the roll 52, and these teeth intermesh with the teeth of a spur gear 56. Compounded with the spur gear 56 is a bevel gear 58 which meshes with a bevel gear 60 that is secured to the lower end of a suitably journaled intermediate driving shaft 62. The shaft 62 is provided, at its upper end with a worm 64 which drives a worm wheel 66 that is fixed on a shaft 68, the latter being the cam shaft which actuates and controls the various operating mechanisms of the machine 10.

The clutch member 46 is adapted to be shifted lengthwise of the shaft 14 to disengage it from the clutch member 44, and in order that it may be permanently maintained in driving relation with the rest of the driving connections 16, the teeth 54 are made wide enough to remain in mesh with the teeth of the spur gear 56 irrespective of the position of the clutch member 46 on the shaft. The clutch member 46 is normally held yieldingly in driven relation with the clutch member 44 by means of a tension spring 70. The spring 70 acts through a lever 72, one end of the spring being connected with the lever and the opposite end with a tension varying device hereinafter 130

described. The lever 72 is fulcrumed at 74 and the upper end thereof is bifurcated to straddle the clutch member 46. The bifurcated ends of the lever 72 are provided with 5 rolls 76 that project inwardly therefrom into an annular groove 78 in the clutch member 46.

Under normal operating conditions the tension of the spring 70 and the pitch of 10 the inclined driving face 50 are such that the clutch member 46 is held in driving engagement with the clutch member 44. When the machine 10 is subjected to a certain amount of resistance or overload tending to 15 hold the machine and clutch member 46 against rotation, the inclined driving face 50 on the fixed clutch member 44 will act upon the roll 52 to force the sliding clutch member 46 lengthwise of the shaft 14 against the 20 tension of the spring 70, thus immediately disengaging the clutch members and disconnecting the machine 10 from the main driving shaft. By adjusting the tension of the spring 70, the safety clutch may be set to 25 trip or disconnect the machine 10 from the shaft 14 at any desired load conditions whereby the machine may be protected from injury due to abnormal loads.

Immediately after the machine 10 is disconnected from the driving shaft 14, the driving shaft is disconnected from its source of power. This is accomplished by means of connections between the lever 72 and the rock shaft 42. These connections 35 comprise a link 80, one end of which is connected to an extension 82 of the lever 72, and an arm 84, which is secured to the rock shaft 42 and connected at 86 to the opposite end of the link 80. The clutch controlling lever 32 is normally maintained with the inclined cam face 31 in raised or 40 inoperative position, out of the path of the wedge blocks 30, as shown in Figs. 1 and 4. When the clutch member 46 is shifted out of 45 driven relation with the driving clutch member 44, the lever 32 is actuated to lower the cam face 31 into the path of the wedge blocks 30 and the main clutch members 20 and 22 are disengaged to disconnect the 50 shaft 14 from the source of power.

In order that the clutch member 46 may be held in its disengaged inoperative position, against the tension of the spring 70, and that the clutch controlling lever 32 may be 55 held in lowered position in engagement with one of the wedge blocks 38, means is provided for latching the lever 72 in the position into which it is swung by the shifting of the clutch member 46 under overload 60 conditions. This means comprises a latch lever 90 that is pivotally hung on a stud 92 and is normally maintained by means of a spring 94, with its lower end bearing against the end of an arm 96, which extends laterally 65 from the lever 72, as shown in Fig. 1.

When the clutch member 46 is shifted out of engagement with the driving clutch member 44, the bottom of the latch lever 90 is permitted to swing above the end of the arm 96, as shown in Fig. 6. A shoulder 97 which is 70 formed in the upper edge of the arm 96, near the end thereof, serves as a stop to limit the swinging movement of the latch lever 90 above the arm 96.

When the machine 10 is to be again connected with the driving shaft 14 by re-engaging the safety clutch, the latch lever 90 is tripped to release the lever 72, and in order that this shall occur at the proper time, the tripping means is controlled by a 75 timing device, which is indicated generally at 98, and which is rendered operative by the stopping of the machine 10 when it encounters an obstruction or overload. The controlling action of the timing device 98 is initiated by the continued rotation of the driving shaft 14 under momentum, after it has been disconnected from its source of power by the disengaging of the main 80 clutch members 20 and 22, and thereafter by the rotation of the driving shaft when it is again started into operation, after the obstruction or overload has been removed from the machine 10, and the operator has manually thrown in the main clutch members 20 and 22. The main clutch is connected manually by the operator lifting a handle 21 (Fig. 4), attached to the lever 32, which removes the cam 31 from its engagement with the wedge blocks 30 and permits the spring 29 to advance the clutch engaging pins 27. The resultant movement of the lever 32 lowers the rod 33, through the block 38, to a position where the latch 36 may re-engage 90 the collar 37 after the sleeve 38 has been lowered by a reconnection of the safety clutch through the means hereinafter to be described.

The timing device operates to effect the release of the lever 72, upon the completion of a certain number of revolutions of the driving shaft, following the disengaging of the members of the safety clutch. The number of revolutions required to effect the release of the lever 72 is determined by the 100 number required to drive the machine 12 through one complete cycle of operations. When the lever 72 is released, the spring 70 returns the clutch member 46 into engagement with the clutch member 44 at such a time that the machine 10 is reconnected to the driving shaft 14 in the same timed relation with the machine 12, or such other machines as may be driven from the main driving shaft 14, as obtained when the machine 105 was disconnected.

The timing device comprises two cooperatively rotary timing members 100 and 102 which are independently driven by two sets 110 of differential gearing 104 and 106, respec- 120 125 130

tively. The timing members 100 and 102 each consists of a disk which is rotatably mounted on a shaft 108 that is fixed in lugs 110 on the frame of the machine 10. The 5 timing member 100 is provided with a lug 112 (Fig. 2) extending laterally from the periphery thereof and carrying a roll 114. The timing member 102 is adapted for lateral movement on the shaft 108, toward 10 or away from the member 100 and is provided with a laterally projecting annular flange 116. The flange 116 extends in the path of the roll 114 for a portion of the distance around the shaft 108 and terminates 15 in inclined cam faces 118 and 120, between which is normally located the roll 114 of the timing member 100.

The gearing 104, by means of which the timing member 100 is operated, includes a 20 gear 124, which is rotatably mounted on the shaft 108. Journaled in a bearing 126 that is formed in the gear 124, is a shaft 128, to the opposite projecting ends of which are severally secured two pinions 130 and 132, 25 which mesh with gears 134 and 136, respectively, that are mounted on the shaft 108, on opposite sides of the gear 124. The gear 134 is free to rotate on the shaft and is secured to the timing member 100. The 30 gear 136 contains one less tooth than the gear 134, and is fixed to the adjacent lug 110 so that it is held stationary.

The gearing 106, which actuates the timing member 102, includes a gear 140, which 35 is rotatably mounted on the shaft 108. A shaft 142 is journaled in a bearing 144 that is formed in the gear 140, and at the opposite ends of the shaft are severally secured two pinions 146 and 148, which mesh with gears 40 150 and 152, respectively, that are mounted on the shaft 108, one on each side of the gear 140. The gear 150 is rotatable on the shaft 108 and is secured to the timing member 102. The gear 152 contains one less 45 tooth than the gear 150 and is held from rotation on the shaft by means of a lever 154 which is fulcrumed at 156 and is provided with a bifurcated upper end that embraces the hub of the gear 152 and is pivotally connected thereto at 158. The gears 140, 150 and 152 are adapted for lateral movement 50 on the shaft 108 so that the group of gearing 106 may move laterally with the timing member 102. The lever 154 is acted upon, 55 below its fulcrum, by a tension spring 160 which presses the gearing 106 and the timing member 102 toward the timing member 100.

In order that the timing members 100 and 60 102 may reproduce the normal stepped time relation between the driven mechanisms and also the out-of-step relation when one of said driven mechanisms is disconnected from the main driving shaft, the gearing 104 is 65 connected with the machine 10 by means

of a gear 162 that is secured to the clutch member 46 and drives the gear 124, while the gearing 106 is connected with the driving shaft 14 by means of a gear 164 that is fixed on the driving shaft and drives the 70 gear 140. The gear 162 is made with teeth of such width that they will remain in mesh with the teeth of the gear 124 when the clutch member 46, carrying the gear 162, is shifted. The teeth of the gear 164 are wide 75 enough to permit the gear 140 to be shifted toward the left on the shaft 108 without getting out of mesh with the gear 164.

With the above described arrangement of 80 gearing, it will be apparent that each time the gears 124 and 140 have made one complete revolution and the pinions 132 and 148 have been carried once around the gears 136 and 152, respectively, the gears 134 and 150 will have been rotated relatively to the gears 85 136 and 152, each through the space of one tooth in the same direction, and consequently the timing members 100 and 102 will have been advanced through a small part 90 of a revolution. The number of teeth in each of the gears 134 and 150 is the same and is determined by the ratio between the driving shaft 14 and the cam shaft 68, being equal to the number of revolutions made by the driving shaft for each revolution of 95 the cam shaft. The ratio between the individual members of both sets of gearing 104 and 106 being the same, both timing members 100 and 102 will be thus slowly advanced at the same rate of speed, and consequently their relative radial positions will 100 remain the same.

The timing members are thus rotated in unison, or in step during normal operating 105 conditions in the machine 10. When, however, the machine becomes obstructed or overloaded, and the timing member 100 by reason of its connection thereto, is held from rotation, the continued turning of the member 102, due to the turning of the driving shaft under momentum after being disconnected from its source of power, causes the cam face 118 to ride over the roll 114, thus shifting the member 102 to the left on the shaft 108. As the member 102 continues to 110 rotate slowly, the edge of the flange 116 rides over the roll 114 and serves to prevent the restoration of normal relationship 115 between the timing members.

Before the driving shaft is again started, 120 the operator removes the obstruction or remedies the difficulty causing the overload. It will be apparent that inasmuch as the machine 10 is completely disconnected from the common driving shaft 14, and left in a neutral condition, upon the occurrence of a predetermined overload, its parts are then 125 free to be manipulated as desired by the operator to facilitate the removal of an obstruction without the possibility of injury 130

to the operator or to the apparatus from sudden movements of the mechanism.

After the cause of the overload has been removed, the main clutch operating lever 5 32 is then operated manually through the hand lever 21 to effect the engagement of the main clutch members 20 and 22 and start the driving shaft 14. The timing member 102 will be held in its shifted position 10 against the action of the spring 160, by the flange 116, until the driving shaft has completed the predetermined number of revolutions hereinbefore referred to, after which the cam face 120 at the opposite end of the 15 annular flange 116 reaches the roll 114, and the member 102 will be permitted to return to its initial relation with the member 100.

The return movement of the timing member 102 and the differential gearing 106, under the action of the spring 160, is utilized 20 to effect the tripping of the latch lever 90, which releases the lever 72 and permits the clutch member 46 to return into engagement with the clutch member 44, to reconnect the 25 machine 10 with the driving shaft. This is accomplished by means of a trip bar 166 which is pivoted at 168 to the lower end of the lever 154, as shown in Fig. 1. The trip bar 166 is provided, at its free end, with a 30 shoulder 170 which is adapted to engage a lateral extension 172 that is formed at the bottom of the latch release lever 90.

When the timing member 102 is forced away from the timing member 100, the shifting movement of the gearing 106 swings the lever 154 so as to move the shouldered end of the trip bar 166 into operative relation with the latch lever 90, as shown in Fig. 7, and when the timing member is returned to 40 its normal position by means of the spring 160, the trip bar 166 trips the latch lever 90 and releases the lever 72. As the lever 72 returns to its normal position, a projection 174, on the arm 96, engages a tail 176 that is formed at the shouldered end of the trip bar 166 and lifts the shoulder 170 out of engagement with the lateral extension 172 of the latch lever 90, as shown in Fig. 1, so that the latch lever will be free to engage the end 45 of the arm 96 the next time the safety clutch is released. The return movement of the lever 72 operates through a link 80 to lower the sleeve 38 and permit the latch 36 to engage the collar 37 on rod 33 thus holding 50 the cam face 31 in its inoperative position, in which it has been placed by lifting the handle 21 attached to the lever 32. An adjusting screw 178 acts as a stop to limit the movement of the lever 154 under 55 the influence of the spring 160. By means of the adjusting screw 178 the shouldered end of the trip bar 166 may be adjusted relatively to the latch release lever 90 so as to insure the tripping of the latter.

When the lever 72 is released the machine

10 will be reconnected with the driving shaft 14 at the same point in the cycle of operations of the machine 12 at which it was disconnected therefrom and the two machines will continue to operate in step or predetermined timed relation.

While, in the drawings, the ratio between the driving shaft 14 and the cam shafts of each of the machines 10 and 12 is the same, and while said ratio is also equal to the ratio between each of the driving gears 162 and 164 and the timing members 100 and 102 respectively driven thereby, it is to be understood that such equality of ratios is not essential in either case but that any or all of the ratios 75 may be varied, it being necessary only that, under normal operating conditions, one of the machines shall perform one or more complete cycles of operation for each cycle performed by the other machine.

The load upon the driven parts of the machine upon which the safety clutch is employed may be unequally distributed throughout different parts of its cycle of operations, the load at one part of a cycle being considerably in excess of the load at another part of the same cycle. In order that the safety clutch shall fully protect the machine during all portions of its cycle of operations, irrespective of the variation and distribution 90 of load throughout the cycle, means is provided for automatically varying the setting or adjustment of the safety clutch at different parts of each cycle.

This means comprises a cam 180 (Fig. 1) 100 on the cam shaft 68, and a cam lever 182 which is fixed to a rock shaft 184 that is suitably journaled in a bearing on the frame of the machine and is provided at its upper end with a cam roll 186 which enters a peripheral groove in the cam. The rock shaft is provided with a downwardly extending arm 188 which is connected with one end of the spring 70. By means of the cam 180 the arm 188 is actuated to increase or diminish 105 the tension of the spring 70 at the required periods in each cycle of operations. The cam 180 is designed with relation to the distribution of load on the driven mechanism throughout the cycle and varies the setting or adjustment of the safety clutch. Thus the setting of the safety clutch is automatically regulated so that the machine is thoroughly protected throughout each portion 110 of its cycle of operations.

While it is preferred to employ the specific construction and arrangement of parts herein shown and described, it will be understood that this construction is not essential except so far as specified in the claims 115 and may be modified without departing from the broader features of the invention.

The invention having been described, that which is claimed as new is:—

1. A stop mechanism having, in combi-

nation, a driving member, a plurality of mechanisms driven therefrom in predetermined timed relation with each other, a clutch normally connecting said driving member and one of said driven mechanisms and adapted to be released under predetermined load conditions on the mechanism driven therethrough, and automatic means for causing said clutch to reconnect said driving member and said clutch driven mechanism so that the time relation between the clutch driven mechanism and the other driven mechanism will be the same as before the clutch was released.

15 2. A stop mechanism having, in combination, a driving member, a plurality of mechanisms driven therefrom in predetermined timed relation with each other, a clutch normally connecting said driving member and one of said driven mechanisms and adapted to be released under predetermined load conditions on the mechanism driven therethrough, and means cooperating with said driving member and said clutch driven mechanism for automatically preventing the reconnection thereof by the clutch except at such time that the time relation between the clutch driven mechanism and the other driven mechanism will be the same as before the clutch was released.

30 3. A stop mechanism having, in combination, a driving member, a plurality of mechanisms driven therefrom in predetermined timed relation with each other, a clutch normally connecting said driving member and one of said driven mechanisms and adapted to be released under predetermined load conditions on said clutch driven mechanism, and an automatic timing device comprising cooperating timing members and two sets of differential gearing respectively connected to the clutch driven mechanism and the driving member for causing said clutch to reconnect said driving member and said clutch driven mechanism so that the time relation between the clutch driven mechanism and the other driven mechanism will be the same as before the clutch was released.

45 4. A stop mechanism having, in combination, a driving member, a mechanism driven therefrom, a clutch normally connecting the driving member and the driven mechanism and adapted to be released under predetermined load conditions on said driven mechanism, and automatic means for restoring the clutch to operative driving condition after a predetermined number of complete revolutions of the driving shaft following the release of said clutch.

60 5. A stop mechanism having, in combination, a driving member, a mechanism driven therefrom, a clutch normally connecting the driving member and the driven

mechanism, and adapted to be released under predetermined load conditions on said driven mechanism, a latch for retaining the clutch in released condition, means for tripping the latch to restore the clutch to operative driving condition, and a timing device for controlling said tripping means.

65 6. A stop mechanism having, in combination, a driving shaft, a mechanism driven therefrom, a clutch for connecting the driving shaft and the driven mechanism comprising a driving member and a normally driven member held yieldingly in engagement with the driving member and adapted to be disengaged therefrom under predetermined load conditions on the driven mechanism, means for holding said normally driven clutch member in disengaged position, and means operative to release the holding means after a predetermined number of revolutions of the driving shaft.

70 7. A stop mechanism having, in combination, a driving member, a mechanism driven therefrom, a clutch for connecting the driving member and the driven mechanism comprising cooperating members arranged to be disengaged under predetermined load conditions on the driven mechanism, means for actuating the driving member, means for throwing out the actuating means by the disengagement of the clutch members, and a timing device for controlling the subsequent engagement of the clutch members.

75 8. A stop mechanism having, in combination, a driving member, a mechanism driven therefrom, a clutch normally connecting the driving member and the driven mechanism and adapted to be released under predetermined load conditions on the driven mechanism, means for actuating the driving member, means for throwing out the actuating means by the release of the clutch, and an automatic timing device comprising cooperating timing members normally driven in unison and adapted to be thrown out of normal relation with each other by the rotation of the driving member under momentum after being disconnected from said actuating means and to be restored to normal cooperative relation to reconnect the driving member and the driven mechanism after said actuating means has been reconnected to said driving member and has caused it to complete the balance of a predetermined number of revolutions.

90 9. A stop mechanism having, in combination, a driving member, a mechanism driven therefrom, a clutch for connecting the driving member and the driven mechanism comprising cooperating members arranged to be disengaged under predetermined load conditions on the driven mechanism, means for actuating the driving member, means for throwing out the actuating means by the relative disengaging movement of the clutch

members, and means rendered operative by said load conditions for effecting the re-engagement of the clutch members only after a predetermined amount of movement of the driving member has taken place upon re-actuation of said driving member.

10. A stop mechanism having, in combination, a driving member, a mechanism driven therefrom, a clutch for connecting the driving member and the driven mechanism comprising cooperating members arranged to be disengaged under predetermined load conditions on the driven mechanism, means for actuating the driving member, means for 15 throwing out the actuating means by the relative disengaging movement of the clutch members, and timing means comprising independently driven members normally moving in unison in one direction and adapted 20 to be moved relatively to each other by the driving member after the disengagement of said clutch members to cause the driven mechanism to be connected with the driving member after a predetermined amount 25 of movement of the driving member has taken place.

11. The combination, with a driving shaft and a plurality of mechanisms driven therefrom, of a stop mechanism comprising a 30 clutch for connecting the driving shaft and one of the driven mechanisms, said clutch being adapted to be thrown out of engagement under predetermined load conditions on the clutch driven mechanism, means for 35 simultaneously disconnecting the driving shaft from its source of power, and means rendered operative by said load conditions for effecting the subsequent engagement of the clutch members at such a time, after re- 40 actuation of the driving mechanism, that said previously disconnected driven mechanism will operate in a predetermined timed relation with the other mechanism driven from said driving shaft.

45 12. A stop mechanism having, in combination, a driving member a mechanism driven therefrom normally adapted to be subjected to different loads during different parts of each cycle of operations, a clutch 50 normally connecting the driving member and the driven mechanism and adapted to be released under predetermined load conditions, and means for automatically adjusting the setting of the clutch in accordance 55 with varying load conditions at different parts of each cycle of operation to predetermine the amount of load required to release the clutch.

60 13. A stop mechanism having, in combination, a driving member, a mechanism driven therefrom, a clutch comprising cooperating members for connecting the driving member and the driven mechanism, a spring for yieldingly holding the clutch

members in operative driving relation, and 65 means for automatically varying the action of the spring upon the clutch members at different parts of each cycle of operations of the driven mechanism.

14. A stop mechanism having, in combination, a driving member, a driven mechanism, a safety clutch normally connecting said driving member and said driven mechanism, and automatic means including cam-controlled apparatus operated by said driven 70 mechanism for adjusting the setting of said clutch to cause it to be released under different load conditions during different parts of the cycle of operation of said driven mechanism.

15. A stop mechanism having, in combination, a driving member, a driven mechanism, a safety clutch normally connecting said driving member and said driven mechanism and comprising cooperating clutch 85 members and means for holding said clutch members in driving engagement, and automatic means for adjusting said holding means to permit said clutch to be released under different load conditions.

16. A stop mechanism having, in combination, a driving member, a driven mechanism, a safety clutch normally connecting said driving member and said driven mechanism and adapted to be released under predetermined load conditions on said driven mechanism, and automatic means for adjusting the setting of the clutch during the operation of said driven mechanism to cause the clutch to be released under different load 100 conditions of said driven mechanism.

17. A stop mechanism having, in combination, a driving member, a mechanism driven therefrom normally adapted to be subjected to different loads during different parts of its cycle of operations, and a clutch normally connecting said driving member and driven mechanism constructed and arranged to be released under different predetermined load conditions at different parts 105 of each cycle of operations.

18. A stop mechanism having, in combination, a driving member, a plurality of mechanisms normally driven therefrom in predetermined timed relation with one another, a clutch normally connecting said driving member and one of said driven mechanisms and adapted to be released under predetermined load conditions on said clutch-driven mechanism, and an automatic 115 timing device comprising cooperating timing members operable upon the release of said clutch to reproduce the out of step relation then existing between the driving member and the clutch-driven mechanism 120 for causing the clutch to reconnect the driving member and the clutch driven mechanism so that the time relation between the

latter and the other driven mechanism will be the same as before the clutch was released.

19. A stop mechanism having, in combination, a driving member, a mechanism driven therefrom, a clutch normally connecting the driving member and the driven mechanism and adapted to be released under predetermined load conditions on said driven mechanism, a latch for retaining the clutch in released condition, and means controlled by the succeeding revolutions of said driving member for tripping the latch to restore the clutch to operative driving condition.

20. A stop mechanism having, in combination, a driving member, a driven member, means normally connecting said members, means for rendering inoperative said connecting means upon the occurrence of predetermined load conditions upon the driven member, and means for effecting the reconnection of said members upon the completion of a predetermined amount of motion of the driving member following the disconnection of said member from the driven member.

21. A stop mechanism having, in combination, a driving shaft, a mechanism driven thereby, a clutch normally connecting the driving shaft and the driven mechanism and adapted to be released upon the occurrence of predetermined load conditions upon the driven mechanism, means for holding the clutch in released condition, and means for releasing said holding means to restore the clutch to normal driving condition upon the completion of a predetermined number of revolutions of the driving shaft following the release of said clutch.

22. A stop mechanism having, in combination, a driving member, means for connecting the driving member with a source of power, a plurality of mechanisms driven from the driving member in predetermined timed relation with each other, a clutch normally connecting the driving member with one of said driven mechanisms and adapted to be released under predetermined load conditions on the mechanism driven therethrough, means for rendering inoperative said connecting means upon the release of said clutch, and means for causing said

clutch to reconnect said driving member and said clutch driven mechanism after the reconnection of the driving member with its source of power so that the timed relation between the clutch driven mechanism and the other driven mechanism will be the same as before the clutch was released.

23. A stop mechanism having, in combination, a driving member, a main clutch for connecting the driving member with a source of power, a plurality of mechanisms driven from the driving member in predetermined timed relation to each other, a safety clutch normally connecting said driving member with one of said driven mechanisms and adapted to be released under predetermined load conditions on the mechanism driven therethrough, means for throwing out the main clutch to disconnect the driving member from its source of power upon the release of the safety clutch, and means for causing the safety clutch to reconnect said driving member and said clutch driven mechanism after the reconnection by the main clutch of the driving member with its source of power so that the time relation between the clutch driven mechanism and the other driven mechanism will be the same as before the clutch was released.

24. A stop mechanism having, in combination, a driving member, a driven mechanism, a clutch normally connecting the driving member and the driven mechanism and constructed and arranged to automatically release itself under predetermined load conditions on said driven mechanism, a latch for retaining the clutch in released condition, and means for tripping the latch to restore the clutch to operative driving condition.

25. A stop mechanism having, in combination, a driving member, a driven mechanism, a safety clutch normally connecting said member and said mechanism and adapted to be released upon the occurrence of predetermined load conditions upon said mechanism, a main clutch for actuating the driving member, and means for disconnecting said main clutch upon the release of said safety clutch.

ERASTUS E. WINKLEY.
